UNITED STATES PATENT OFFICE.

FLAVIOUS J. HOLLICROFT, OF JENKS, OKLAHOMA.

AUTOMATIC AIR-LINE COUPLING.

1,209,965.

Specification of Letters Patent. Patented Dec. 26, 1916.

Application filed November 30, 1914. Serial No. 874,806.

To all whom it may concern:

Be it known that I, FLAVIOUS J. HOLLICROFT, a citizen of the United States, residing at Jenks, in the county of Tulsa and 5 State of Oklahoma, have invented certain new and useful Improvements in Automatic Air-Line Couplings, of which the following is a specification.

This invention relates to car air line 10 couplers, and more particularly relates to auxiliary coupling devices to automatically couple the extending ends of the train air lines.

As a principal object, this invention 15 templates the provision of an auxiliary coupler which shall so automatically engage the air lines of each car of a train as to obviate the necessity of manual interference between the cars.

20 A further object is to provide a coupler which shall be resiliently engageable to effect a perfect mating joint between the portions of the device carried by separate cars.

It is a further and particular object to 25 provide a device of this character in which shall be incorporated means preventing any displacement of the coupler portions when the train is taking a curve.

An object of equal importance with the 30 foregoing is to provide an automatic auxiliary coupler which shall be constructed of so few and comparatively simple elements as to readily permit of convenient installation, adjustment or replacement of parts.

35 The above and additional objects which will become apparent as this explanatory description proceeds, are accomplished by such means as are illustrated in the accompanying drawings, described in the following specification, and then more particularly pointed out in the claims which are appended hereto and form a part of this application.

With reference to the drawings, wherein 45 there is illustrated the preferred embodiment of this invention as it is reduced to practice and throughout the several views, of which like characters of reference designate similar parts: Figure 1 is a side elevation of a pair of the auxiliary coupler portions as automatically locked upon the coupling of two cars, Fig. 2 is a fragmentary view similar to Fig. 1, showing the coupler portions at their initial moment of contact,

Fig. 3 is a view in longitudinal vertical section taken through meeting coupler portions, Fig. 4 is a sectional view taken on the line 4—4 of Fig. 3, Fig. 5 is a plan view of one of the coupler heads, Fig. 6 is an elevation of a coupler face, and Fig. 7 is an enlarged sectional view of the resilient support for each coupler portion shown in Fig. 3.

With reference to the drawings, the characters A and B denote the sills of a pair of 65 coupled cars, such sills serving to support in the usual manner the draw bars 10 with their customary coupler heads 11 whereby the cars are connected. Below this main coupling is to be situated the automatic air 70 coupling comprehended by this invention and supported by suitable brackets 12 secured to the sills A and B by means 13 and suitably apertured to slidably receive the auxiliary coupling bars 14 which as indicated in Figs. 3 and 4 are preferably square 75 in cross section to prevent undesirable rotational movement. Forwardly each of these coupler bars carries an enlarged head portion 15 to which is secured by removable 80 bolts 16, the main head portion 17 which in case of injury may be thus replaced without necessitating removal of the entire head.

The main head 17 is stepped as indicated 85 at 18 on the upper portion thereof in order to receive the reduced extension 19 of the contact portion of each coupler 20. This extension 19 is formed with the conical stem 21 which extends through a suitable and similarly shaped seat formed in the main 90 head 17 projecting therefrom on the lower side to receive the lock nuts 51 between which and the underface of the head is interposed the expansible resilient means 22 which maintains the stem firmly in its 95 proper position. Extending over the upper surface of the step 18 is an integral finger 23 formed upon the extension 19 for contact with suitable stops 24 carried by the main head in the manner clearly illustrated 100 in Fig. 5 in order to limit swinging movement of each coupler head.

Each of the meeting portions 20 is formed with a pyramidal recess 25 the mouth of which is surrounded by a resilient gasket 105 26 formed preferably of rubber and secured to the face of the portion 20 by some means such as 27. At the central inner portion of

the pyramidal recess there connects the duct or passageway 28 from the stem 19 whence it extends downwardly as indicated at 29 into the stem 21 which is provided with a 5 cut out portion 30, as shown in Fig. 4 in order to permit of communication between the passageway 29 and horizontal passageway 31 extending through the bar 14. The rearward extremity of this bar is provided 10 with a recess 32 in which is seated an expansible coiled spring 33 also surrounding the projecting extremity 34 of the train air line 35 suitably supported in a bracket device 36. A stop 37 is carried by the bar 14 15 in order to limit the movement of the coupler as determined by the spring 33.

From the foregoing, it will be apparent that the operation of this automatic coupler is as follows: Under the influence of the 20 rear spring 33 the coupler is resiliently supported in that position illustrated in Fig. 2 with the enlarged head 20 projecting some distance beyond the upper main coupler head 11. Upon the approach of a second 25 car similarly equipped with a projecting coupler head these latter engage with their meeting gaskets 26 in contact while the nearer approach of the two cars forces the couplers against the action of the springs 33 30 backward through the supports 12 until the stems 34 of the train air line enter the rear recesses 32 and establish communication with the ducts 31, whereby the air is enabled to flow from the train line through one of 35 these ducts and the duct 29 through the common chamber formed by the meeting recesses 25 and similarly through the second coupler to conduct the air line the length of the train.

40 It will be apparent that means have been thus provided whereby the previously presented objects of this invention may be accomplished and that this invention may accordingly be claimed as possessing the 45 advantages and desirability set forth in such objects.

What is claimed is:

1. In an auxiliary coupling device of the type set forth, a stepped head, a conical passage formed in said head, a coupling head, and a stem formed on said coupler adapted 50 to be supported in said passage to pivotally mount the coupler.

2. In an auxiliary coupler of the type set forth, a stepped head, a coupler resting in the stepped portion of said head, a conical passageway formed in said head, an integral stem formed on said coupler and extending into said passageway to pivotally mount 55 said coupler, and means preventing the unseating of said stem from said passage.

3. In an auxiliary coupler of the type set forth, including a stepped head, a conical passageway formed in said head, a recessed 60 coupler resting on the stepped portion of

said head, a stem formed integrally with said coupler and seated in said passageway, and a passage connecting through said stem and said coupler with the recess of the latter.

4. In an auxiliary coupler of the type set forth including a stepped head, a conical passageway formed in said head, a coupler provided with a pyramidal recess and resting on the stepped portion of said head, a 75 stem formed integrally with said coupler and seated in said passageway, a passage connecting through said stem and said coupler with said recess, and a resilient gasket adapted to inclose said recess to form 80 an air tight contact with a similar coupling device.

5. In an auxiliary coupler of the type set forth, a stepped head, a coupler resting in the stepped portion of said head, a conical 85 passageway formed in said head, an integral stem formed on said coupler and extending into said passageway to pivotally mount said coupler for a swinging movement, means preventing the unseating of said stem 90 from said passageway, and stop means limiting such swinging movement.

6. An auxiliary coupler of the type set forth including a head, a body portion mounted for longitudinal reciprocation, resilient means normally tending to maintain said coupler at its outermost limit, a stepped head removably secured to said first head, a conical passageway formed in said head, a coupler provided with a coned stem for 95 seating in said passageway, a communicating channel adapted to make connections with said stem, and means normally preventing the unseating of said stem as and for the purpose set forth.

7. An air line coupler of the type set forth including a bar formed with a longitudinal passage and having one end recessed to communicate with said aperture, an enlarged head formed on said bar, a stepped head 110 removably secured to said first head, a coupler pivotally mounted within said stepped head, a stop arm carried by said coupler, coacting stop means secured to said stepped head, a train line pipe projecting into said 115 bar recess for communication with said passage, and resilient means surrounding said pipe and receivable within said recess for separating said pipe and said bar.

8. A train air line coupler including a 120 supporting bracket, a bar reciprocable within said bracket and formed with a longitudinal passage, a stepped coupler head carried by said bar, a coupler pivotally mounted in said stepped head, coacting stop means limiting pivotal movement of said coupler with respect to said head, a train air line pipe aligned with the passage in said bar, means normally separating said pipe and said bar but compressible to permit communication 125 130

between said pipe and said passage, means for continuing said passage through said pivoted coupler, and stop means carried by said bar and coacting with said bracket for 5 limiting movement of separation between said bar and said pipe.

In testimony whereof I affix my signature in presence of two witnesses.

FLAVIOUS J. HOLLICROFT.
